TOOTHPICK DISPENSER

John L. Young, Chicago, Ill.

Application January 16, 1935, Serial No. 2,091

2 Claims. (Cl. 312—83)

This invention relates to an automatic dispenser for dispensing tooth picks and the like.

The main object of the invention is to provide an automatic dispenser for dispensing tooth picks in a sanitary manner.

Another object of the invention is to guide the tooth picks down a chute and regulate the output of the dispenser.

A still further object of the invention is to facilitate the dispensing of the tooth picks by vibrating the magazine and thus preventing the tooth picks from "caking".

Other objects will appear as the disclosure progresses. The drawing is intended to merely indicate a possible embodiment of the invention. It is obvious that the actual needs of manufacture may necessitate certain mechanical changes. It is therefore not intended to limit the embodiment of the invention illustrated but rather to define such limits in the appended claims. For a more general understanding of the invention attention is called to the drawing in which

Figure 1 is a sectional view of the tooth pick dispenser.

Figure 2 is a section on line 2—2 of Figure 1. Figure 3 is a modified form of the dispenser.

Figure 4 is a section on line 4—4 of Figure 3.

Figure 5 is an enlarged detail of a portion of the dispenser illustrated in Figure 3.

Referring now to the drawing in detail, numeral 1 designates the casing, 2 the magazine and 3 the chute. The casing is provided with a removable cover 4 and an inner shoulder 5 for supporting the magazine. The upper portion 6

35 of the lower end of the chute is hinged as at 7 and is provided with a downwardly bent lip 8 resting on the lower portion 9 of the chute. Attached to the interior of the chute is a rigid guide 10 for gradually forming the mass of tooth picks 40 into one layer so the output of the magazine can be regulated. In the interior of the casing is a plunger 11 for operating the hinged portion 6 of the chute. The bottom of the plunger is linked to a lever 12 fulcrumed on the vertical

45 post 13. The outward end 14 of the lever is bent upwardly and is connected to the hinged end 6 of the chute. Numeral 16 designates a set of springs for normally keeping the hinged end 6 of the chute in a closed position. When the plunger 11 is pressed down against the compression spring 15 the end 14 of the lever will uplift the hinged portion 6 of the chute and allow the tooth picks 15a to slide down the inclined lower portion 9 of the chute where they can be picked up.

50 When the lever is released the springs 16 will shut the hinged portion 6 and the flow of tooth picks will stop.

In the form of the invention shown in Figure 3, numeral 17 designates the casing, 18 the magazine and 19 the chute. The casing is provided with a removable top cover 20 and an inner shoulder 21 for supporting the magazine. Both the upper and lower walls 22 and 23 of the chute are hinged to the magazine by the hinges 24 and 25 respectively. Attached to the end of the wall 10 522 by the hinge 26 is a swinging element 27. Numeral 28 designates a plunger for operating the chute, 29 the spring for normally keeping the plunger in an upper position and 30 the inclined tray for collecting the tooth picks. Beneath the 15 chute are two compression springs 31 and 32.

The operation of this form of the invention is as follows:

The tooth picks 33 contained in the magazine when reaching the downwardly sloping portion 20 34 at the end of the wall 22 will separate into one layer and stop at the wall 35 of the element 27. When the plunger 28 is pressed down the hinged chute will swing down against the springs 31 and 32 as shown in dotted lines in Figure 5 25 25 and the swinging element 27 will catch on the shoulder 36 and hold said element in a suspended position and thereby permit the tooth picks to leave the chute. When the plunger is released the chute will swing up and the element 30 30 35 35 40 will swing down thus stopping the flow of tooth picks. From the above description it will be apparent that the swinging element 27 acts as a valve to shut off or admit the tooth picks to enter the tray 30. The vibration due to the up and down movement of the chute caused by the operation of the plunger will at the same time keep the mass of tooth picks loose and prevent their "caking" thus allowing them to flow out smoothly and evenly.

It will thus be seen that I have provided a sanitary tooth pick dispenser which is simple in construction and efficient in operation. The rate of flow and the amount of tooth picks dispensed at one time is uniformly regulated.

Having described my invention, I claim:

1. In a device of the class described, a casing, a magazine for holding tooth picks in said casing, a chute, said chute being hinged to said magazine, a plunger for vibrating said chute, a tray at 50 the termination of said chute for collecting said tooth picks, said chute comprising upper and lower wall members, a swinging element attached to said upper wall member, said element adapted to admit the tooth picks in said tray when raised 55

up and to shut off the supply when moved downwardly.

2. In a device of the class described, a casing, a magazine for holding tooth picks in said casing, a chute, said chute being hinged to said magazine, a plunger for vibrating said chute, a tray at the termination of said chute for collecting said tooth picks, said chute comprising upper and lower wall members, the said upper and lower

wall members being hinged to the lower end of said magazine for up and down movement relative to said magazine, a swinging element attached to said upper wall member, said element adapted to admit the tooth picks in said tray when raised up and to shut off the supply when moved downwardly. 5

JOHN L. YOUNG.
